KERF CUTTING MACHINE

William T. McCullough, Chicago, Ill., assignor to
 Goodman Manufacturing Company, Chicago,
 Ill., a corporation of Illinois

Application October 22, 1934, Serial No. 749,345
 Renewed May 5, 1937

10 Claims. (Cl. 262—28)

This invention relates to improvements in kerf-cutting machines of the low vein track-mounted type particularly adapted to cut a kerf in front of and to each side of the track along the mine bottom or at various elevations with respect thereto.

Among the objects of my invention are to provide a new and improved mining machine of the class described, arranged with a view towards 10 compactness, especially in vertical dimensions, and accessibility, flexibility and efficiency in operation.

My invention may be more clearly understood with reference to the accompanying drawings 15 wherein:

Figure 1 is a top plan view of a mining machine having the principles of my invention embodied therein;

Figure 2 is an enlarged view in side elevation 20 of the forward portion of the device shown in Figure 1 with parts shown substantially in longitudinal section;

Figure 3 is an enlarged fragmentary view in side elevation of the rearward portion of the device shown in Figure 1 with parts broken away and shown substantially in longitudinal section;

Figure 4 is an enlarged fragmentary plan view of the forward portion of the device shown in Figure 1 with parts broken away and shown in 25 horizontal section;

Figure 5 is an enlarged detail fragmentary sectional view of the cutter bar swinging mechanism taken substantially along line 5—5 of Figure 4;

Figure 6 is an enlarged detail plan view of the 30 cutter bar tilting mechanism with parts shown in horizontal section;

Figure 7 is a sectional view taken substantially along line 7—7 of Figure 6; and

Figure 8 is an enlarged detail view of the locking mechanism for the turntable.

Like reference characters refer to like parts throughout the various figures.

In the drawings, the machine illustrated includes a truck 10 mounted on track wheels 11, 11 45 and axles 12, 12. A turntable 13 is mounted on the forward end of said truck and forms a support for a cutting element, generally indicated by reference character 14.

The mining machine may be propelled about 50 the mine or sumped into and fed across the face of the coal by suitable mechanism actuated by a motor 15, of the usual electric type, mounted on said truck rearwardly of the turntable 13. Said motor is connected with the forward track wheels 55 by means of a suitable train of change speed

reduction gears, generally indicated by reference character 16. Said change speed reduction gears will not herein be shown or described in detail since they are of a usual arrangement and form no portion of my present invention. 5

The change speed reduction gear train 16 also forms a portion of the train of gearing which turns the turntable 13 for swinging the cutting element across the front of and to each side of the truck at either a slow feeding speed or a high 10 positioning speed. The turntable turning mechanism includes a worm and worm gear train driven by the gear train 16 and generally indicated by reference character 17, which mechanism is best shown in Figures 3 and 5. Said 15 worm and worm gear train selectively drives a pinion 18 adjacent the lower end of a vertical shaft 19 through a clutch member, generally indicated by reference character 20 (see Figure 3). Said pinion turns the turntable 13 by means of 20 a gear train, generally indicated by reference character 21, in an obvious manner.

Means are provided for locking said turntable and cutting element in fixed relation with respect to said truck, which means, as herein shown in 25 Figures 3 and 8, comprises a stop member 23 slidably mounted in a guide 24 and adapted to engage jaws 25, 25 extending upwardly from the pinion 18 for holding said pinion and the gear train 21 from movement. 30

A winding drum 26 is freely mounted on the upper end of the shaft 19 and is selectively connected with the worm and worm gear train 17 by means of a jaw clutch, indicated by reference character 27, in an obvious manner. Said winding drum is adapted to serve as a means for feeding the cutting element in cases where the cutting is hard and the tractive effort of the track wheels on the rails is not sufficient to sump said cutting element into the coal or feed said cutting 40 element along the coal face. 35

Referring now in particular to the details of the cutting element 14, said cutting element includes a frame member 29 trunnioned adjacent its rearward end on trunnion supports 30, 30 45 secured to and extending upwardly and forwardly from opposite sides of the turntable 13 and best shown in Figures 1 and 4. Said frame member extends forwardly of said turntable and truck and is provided with a pair of parallel-spaced depending gibbed guides 31, 31 disposed adjacent the forward end of said truck. Said guides are adapted to register with corresponding gibbed guides 32, 32 formed integral with 50 and extending from a second frame member 33 55

(see Figure 4). Said guides are held in engagement with each other by means of retaining strips 34 secured to the rearward face of the guides 32, in a suitable manner, and abutting the rearward face of the guides 31.

A threaded shaft 35 is horizontally pivoted between projections 36, 36 extending forwardly of said second frame adjacent the longitudinal center line thereof. Said shaft is threaded within a threaded sleeve 37 which sleeve is in turn threaded within a threaded hub of a worm gear 38. Said worm gear is journaled in the forward end of the frame member 29 so that rotation of said worm gear in one direction or another will effect movement of said second frame towards or from said first-mentioned frame, in an obvious manner.

The second frame 33 has a cored inside of circular form which is adapted to form a journal for a cutter bar supporting member 39 (see Figure 2). Said cutter bar supporting member has a cutter bar 40 secured thereto in a suitable manner and is held in position in said second frame by means of an annular flange 41 extending inwardly from a spur gear 43 and secured to the upper surface of said cutter bar supporting member and abutting the upper annular surface of said second frame. Said spur gear is meshed with and driven by a spur pinion 44 journaled in said second frame for swinging said cutter bar about its axis of pivotal connection to said second frame.

The cutter bar support member 39 is herein shown as being provided with a central hub portion which is bored along its axis of pivotal connection to said second frame. The bored portion of said cutter bar support member forms a bearing support means for a sleeve 46 which sleeve in turn has a sprocket 47 secured thereto adjacent its lower end. Said sprocket meshes with a cutter chain 48 for driving said cutter chain about the cutter bar 40 in a usual manner. The inside of said sleeve is splined and is adapted to be slidably engaged by a splined shaft 49. The upper portion of said splined shaft is adapted to slidably engage a splined hub 50 of a bevel gear 51 which is journaled on said hub in said first-mentioned frame.

Referring now in particular to the power device which drives the operating parts of the cutting element 14, and the novel arrangement of said power device with respect to the turntable 13, so that the height of the machine may be kept to a minimum, said power device is preferably shown as comprising a motor 53 of the ordinary electric type. Said motor is secured to and extends rearwardly from the first frame 29 and is so arranged with respect to the machine that it determines the height of the machine. In Figures 2, 3 and 4 it will be seen that an opening 54 is provided in said turntable which is of sufficient dimensions to receive a portion of said motor. Said motor extends through said opening in such a manner that its bottom surface is lower than the lowest portion of said turntable. It will be seen that this arrangement reduces the over-all height of the machine in a novel manner and enables a relatively large and powerful motor to be used having sufficient power to efficiently drive the cutting mechanism.

A novel power-operated device driven from the rearward end of the motor 53 is provided for

tilting said cutting element about its axis of pivotal connection to the trunnion supports 30, 30. Said power-operated device is best shown in Figures 3, 6, and 7 and includes a vertically disposed threaded shaft 55 secured adjacent its lower end to a coil spring 56. Said coil spring is secured within a bored portion of the turntable 13 and forms a means for supporting said cutting element for yieldable movement about the axis of said trunnion supports during the cutting operation. Said shaft is guided against axial movement about its lower end and rotatable movement about its longitudinal axis by means of a member 57 secured to the upper portion of said turntable and partially encasing the coil spring 56. Said member has an aperture 58 formed therein which serves as a guide to limit rotation and axial movement of said threaded shaft.

A nut 59 is trunnioned within a member 60 secured to the under surface of a bevel gear 61 journaled within a frame member 62 extending rearwardly from the motor 53. Said nut is threaded on said threaded shaft so that rotation of said bevel gear and nut in one direction or another will cause said nut to move along said threaded shaft to pivot the cutter bar 40 about the axis of the trunnion supports 30, 30.

The means for driving the bevel gear 61 from the motor 53 includes a motor pinion 63 meshing with and driving a spur gear 64 keyed adjacent the forward end of a longitudinally extending shaft 65. Said shaft is journaled within the frame member 62 and has a pair of facing bevel gears 66, 66 freely mounted thereon and journaled on their hubs within said frame member. Said bevel gears mesh with a bevel gear 67 keyed on one end of a shaft 68. A bevel pinion 69 is keyed on the other end of said shaft and meshes with and drives the bevel gear 61.

A suitable clutch means is provided for connecting either of the bevel gears 66, 66 to the shaft 65 to form a means for reversely driving the bevel gear 61 and nut 59 which clutch means, as herein shown, includes a clutch member 70 feathered on the shaft 65 and having oppositely disposed engaging friction surfaces 71, 71 adapted to engage inwardly extending friction surfaces 72, 72 on the facing bevel gears 66, 66. Said clutch member is shifted by means of a clutch yoke 73 pivotally connected to a clutch fork 74 journaled in the frame member 62 for rocking movement with respect thereto. A lever arm 75 is secured to an upwardly extending pin 76 of the clutch fork 74 for rocking said clutch fork and shifting said clutch member. A spring-pressed plunger 77 is carried in said lever arm and is adapted to engage a suitable notch formed in a member 78 secured to the frame member 62 for holding said clutch member in a neutral position. A hand lever 78a is pivotally connected to said lever arm and extends outwardly through an opening in a counterbalance 79 secured to and extending rearwardly from the turntable 13. It should be noted that said hand lever is so arranged as to be readily accessible and be disposed beneath the top of the motor 53.

With reference now in particular to the means for driving the moving parts of the cutting element 14, a motor pinion 80 on the forward end of the shaft of the motor 53 meshes with and drives an internal gear 81. Said internal gear is journaled on its hub in the frame member 29 and is keyed to a rearward end of a longitudinal

shaft 83. It should be noted that the novel arrangement of said motor pinion and internal gear herein illustrated, enables a relatively large reduction to be obtained between said motor and longitudinal shaft without increasing the height of the machine. Said longitudinal shaft is journalled in the frame member 29 in a suitable manner and has a bevel pinion 84 keyed to its forward end which meshes with and drives the bevel gear 51 for driving the cutter chain 48 about the cutter bar 40 through the splined shaft 49 and sprocket 47.

A pair of facing bevel gears 85, 85 are freely mounted on the shaft 83 and journalled on their hubs in the frame member 29. Said bevel gears are selectively connected with said shaft by means of friction clutches 86, 86 operated by a clutch collar 87 in a usual manner. Said bevel gears mesh with and drive a bevel gear 88 on one end of a transverse shaft 89 journalled within the frame member 29. A bevel pinion 90 is on the opposite end of said shaft and meshes with and drives a bevel gear 91 freely mounted on a longitudinal shaft 93. Said bevel gear is journalled on its hub in the frame member 29 and has a spur gear 94 connected thereto for driving said spur gear. The spur gear 94 in turn meshes with a spur gear 95 on a parallel shaft 96. A spur pinion 97 is keyed on the opposite end of said parallel shaft and meshes with and drives a spur gear 98 freely mounted on the longitudinal shaft 93. The spur gears 94 or 98 are operatively connected with the longitudinal shaft 93 for driving said shaft at either a high or low speed by means of a clutch member 99 interposed between said spur gears and feathered on the shaft 93. Said clutch member has internal teeth cut integral with opposite ends thereof which are adapted to mesh with the teeth of the spur gear 94 for driving the shaft 93 at a high speed or with a gear 100 cut integral with the hub of the spur gear 98 for driving said shaft at a relatively low speed.

A worm 101 is keyed on the forward end of the longitudinal shaft 93 and meshes with and drives a worm gear 103. Said worm gear is secured to a flanged sleeve 104 intermediate the ends thereof, which flanged sleeve is journalled in the frame member 29. The inside of said flanged sleeve is splined and is adapted to be engaged by a splined shaft 105, which splined shaft slidably engages the splined hub of the spur pinion 44 and provides an extensible drive connection between said worm gear and spur pinion for swinging the cutter bar 40 at either a high or low frictionally controlled speed in reverse directions without reversal of the motor 53.

The cutter bar 40 is moved towards and from the frame member 29 by means of a spur gear 106 keyed on the hub of the forward bevel gear 85. Said spur gear meshes with and drives a spur gear 107 freely mounted on a longitudinal shaft 108. A sleeve member 109 having internal teeth formed therein is coaxial with the shaft 108 and driven by the spur gear 107. The internal teeth of said sleeve member are adapted to be engaged by corresponding teeth 110 formed integral with a clutch member 111 feather on the longitudinal shaft 108 for selectively driving said shaft. A longitudinal shaft 112 is arranged coaxially with the shaft 108 and is connected thereto by means of a collar 113. A worm 114 is keyed to the forward end of the shaft 112 and meshes with and drives the worm gear 38 for moving the cutter bar 40 either towards or

from the frame member 29 without reversal of the motor 53.

It will thus be seen that by the improved arrangement of gearing shown, the cutter bar 40 may be swung at either a low feeding speed or a relatively high positioning speed in reverse directions without reversal of the motor and that said cutter bar may be adjustably moved towards and from the frame member 29 by means of a separate gear train but through the same reverse gearing as is used for swinging said cutter bar.

It may also be seen that the arrangement of the motor and gearing is such as to be of a compact form and take up a minimum amount of vertical height and still maintain the proper proportions for adequately driving the cutter chain and for swinging or adjusting the cutter bar for performing the cutting operation in a most efficient manner.

While I have herein shown and described one form of my invention, I do not wish to be limited to the precise details of construction or arrangement of parts herein shown and described, excepting as specifically limited in the appended claims.

I claim as my invention:

1. In a mining machine, a track-mounted truck, a turntable on said truck, a cutting element trunnioned on said turntable for pivotal movement about a transverse axis disposed adjacent the forward end thereof, said cutting element including a motor, a frame member disposed forwardly thereof and extending beyond the forward end of said truck, a cutter bar having a cutter chain movable thereabout projecting forwardly of said frame member, and an opening in said turntable adapted to receive the lower portion of said motor and permit pivotal movement of said cutting element and motor with respect to said truck about its axis of pivotal connection to said turntable.

2. In a low vein track-mounted mining machine of the type adapted to cut a kerf in front of and to each side of the mine track adjacent the mine bottom, a truck, a turntable on said truck having an opening therein, a cutting element mounted on said turntable including a frame member extending forwardly of said turntable, a cutter bar having a cutter chain movable thereabout supported by said frame member for pivotal movement about an axis perpendicular thereto, a motor mounted on and extending rearwardly of said frame, said motor extending within said opening beneath the bottom of said turntable, and means driven by the forward end of said motor for swinging said cutter bar and driving said cutter chain about said cutter bar including a motor pinion, a longitudinal shaft, and an internal gear meshing with said motor pinion and driving said longitudinal shaft.

3. In a low vein track-mounted mining machine, a truck including a truck frame supported on track wheels and axles, a turntable mounted on said truck frame and having a major portion disposed beneath the upper margins thereof, a cutting element on said turntable including a cutter bar having a cutter chain movable thereabout, and means for driving said cutter chain about said cutter bar including a motor having its lower portion recessed within said turntable and truck frame.

4. In a low vein track-mounted mining machine, a truck including a truck frame supported on track wheels and axles, a turntable mounted on said truck frame and disposed beneath the

- upper margins thereof, a cutting element on said turntable including a cutter bar having a cutter chain movable thereabout, and means for driving said cutter chain about said cutter bar including 5 a motor having a portion thereof intersected by a plane extending across the top of said truck frame.
5. In a low vein track-mounted mining machine, a truck including a truck frame supported 10 on track wheels and axles, a turntable mounted on said truck frame and disposed beneath the upper margins thereof, a cutting element on said turntable including a cutter bar having a cutter chain movable thereabout, and means for driving said cutter chain about said cutter bar including 15 a motor having a portion thereof intersected by a plane extending along the bottom of said turntable and intersecting said truck frame.
6. In a low vein track-mounted mining machine, a truck including a truck frame supported 20 on track wheels and axles, a turntable mounted on said truck frame and disposed beneath the upper margins thereof, a cutting element on said turntable including a cutter bar having a cutter 25 chain movable thereabout, and means for driving said cutter chain about said cutter bar including a motor, said turntable having an opening therein and said motor extending within said opening and beneath the bottom of said turntable.
- 30 7. In a low vein track-mounted mining machine, a turntable, a cutting element on said turntable including a motor and a projecting cutter bar having a cutter chain movable thereabout, a truck frame supported on track wheels and axles, said truck frame having a recessed portion therein adapted to form a support for said turntable so said turntable may extend beneath the upper 35 margins of said truck frame, and said turntable having an opening in the central portion thereof 40 adapted to receive the lower portion of said motor and permit said motor to be recessed within said truck frame.
8. In a low vein track-mounted mining machine, a turntable, a cutting element on said turntable including a motor and a projecting cutter bar having a cutter chain movable thereabout, a truck frame supported on track wheels and axles, said truck frame having a recessed portion therein adapted to form a support for said turntable 45
- so said turntable may extend beneath the upper margins of said truck frame, and said turntable having an opening in the central portion thereof adapted to receive the lower portion of said motor and permit said motor to extend beneath the 5 lower boundaries of said turntable and be recessed within said truck frame.
9. In a mining machine, a wheel-supported frame having a recess therein and providing an annular bearing, a turntable providing an open-centered turntable ring received in said recess and supported by said bearing, upstanding bearing-providing means supported by said turntable ring, a second frame having trunnions journaled in said bearing-providing means for tilting on 10 a horizontal axis extending transversely of said turntable, a cutter-chain-carrying cutter bar supported at the forward end of said second frame, and an actuating motor for said cutter chain carried by said second frame and having a casing 15 substantially rectangular in central longitudinal section and narrower laterally than said ring opening and having its rear end forward of the rearmost portion of the opening in said turntable ring and tilttable with said second frame and operatively connected to drive said cutter chain, said second frame tilttable about said transverse axis to raise said cutter bar, and said motor, in a tilted position of said second frame, having at least the portion thereof including the rearward end of its casing within the open center of 20 said turntable ring and below the top of said annular bearing.
10. In a low vein mining machine, a truck including a truck frame supported on track wheels 25 and axles, said truck frame having a widely extended upright bearing, a turntable mounted on said frame with an open portion thereof rotatably supported within said bearing, a cutting element including a drive motor and a cutter bar projecting therefrom, mounted on said turntable for pivotal movement as a unit about a transverse axis disposed above said bearing, and the lower portion of said motor extending within said open 30 portion of said turntable beneath the upper limits of said bearing and moving vertically within said open portion during tilting movement of said cutting element about its transverse axis.

WILLIAM T. McCULLOUGH.
